US00D916924S

(12) **United States Design Patent** (10) Patent No.: **US D916,924 S**
(45) Date of Patent: **** Apr. 20, 2021**

(54) **DISPLAY SCREEN OR PORTION THEREOF WITH ICON**

- (71) Applicant: **Apple Inc.**, Cupertino, CA (US)
(72) Inventor: **Raymond Sepulveda**, San Jose, CA (US)
(73) Assignee: **Apple Inc.**, Cupertino, CA (US)
(**) Term: **15 Years**
(21) Appl. No.: **29/722,157**
(22) Filed: **Jan. 27, 2020**

Related U.S. Application Data

- (60) Continuation of application No. 29/672,881, filed on Dec. 10, 2018, now Pat. No. Des. 873,859, which is a continuation of application No. 29/626,800, filed on Nov. 20, 2017, now Pat. No. Des. 835,673, which is a continuation of application No. 29/569,936, filed on Jul. 1, 2016, now Pat. No. Des. 803,263, which is a continuation of application No. 29/459,074, filed on Jun. 25, 2013, now Pat. No. Des. 760,762, which is a division of application No. 29/364,038, filed on Jun. 17, 2010, now Pat. No. Des. 684,987, which is a division of application No. 29/324,935, filed on Sep. 23, 2008, now Pat. No. Des. 618,248.

CLAIM

The ornamental design for a display screen or a portion thereof with icon, as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a front view of a display screen or portion thereof with icon showing the claimed design; and,

FIG. 2 is a front view of another embodiment thereof.

The broken lines in the figures show a display screen or portion thereof, and form no part of the claimed design.

**1 Claim, 1 Drawing Sheet
(1 of 1 Drawing Sheet(s) Filed in Color)**
